UNITED STATES PATENT OFFICE.

PHILLIP HIEN AND ASMUS H. GRIMM, OF ROCK ISLAND, ILLINOIS.

CULTIVATOR.

SPECIFICATION forming part of Letters Patent No. 284,960, dated September 11, 1883.

Application filed April 13, 1883. (No model.)

To all whom it may concern:

Be it known that we, PHILLIP HIEN and ASMUS H. GRIMM, citizens of the United States, residing in Rock Island, Illinois, have invented 5 certain Improvements in Cultivators, of which the following is a specification.

The present improvements relate to the draft apparatus, to the means employed for connecting the cultivator-beams to the arched frame, 10 and to the method of hanging and supporting the bars or runners which are used when the machine is being drawn to and from the field and the beams are elevated, the objects of the improvements being too fully explained hereinafter to need preliminary description. 15

In the accompanying drawings, Figure 1, Sheet 1, is a perspective view of the improved cultivator with both beams elevated; Fig. 2, a perspective view of the arched frame detached; 20 Fig. 3, Sheet 2, a side view of that part of the machine to which our invention relates; Fig. 4, a plan view of the same; and Figs. 5 to 12, inclusive, detached views of parts of the cultivator. The views on Sheet 2 are on a larger scale 25 than Figs. 1 and 2.

A is the arched frame of the cultivator, and to the lower portion of this frame are securely bolted the open side frames, B B, to which are pivoted, in the manner described hereinafter, 30 the cultivator-beams D D, each of the latter being furnished with a suitable handle, as usual. The arched frame consists of a bar, x, with central rib, x', the latter being discontinued some distance from the lower end of each leg of the 35 arch, so as to form seats y for the frames B. The arch thus made possesses the qualities of lightness and strength.

The wheels F F are independent of each other, each wheel being free to turn on a short axle, G, 40 a detached view of which is shown in Fig. 5. This axle has at the inner end a hollow vertical stem, a, which is adapted to eyes b b on one of the frames B, and is confined thereto vertically by means of a cap, d, which bears upon 45 the upper eye, and is secured in place by means of a bolt and nut, as shown in Figs. 5 and 9. By this means each axle is pivoted to the frame B, so as to swing thereon.

Each draft-bar J is hooked at the outer end 50 for adaptation to the eye of the whiffletree, the inner ends of the draft-bars being fitted to the

stems a of the axles, between the eyes b b. From the outer ends of the draft-bars to the outer ends of the axles extend rods K, which are bent so as to accommodate the wheels, the rear ends of the rods fitting over the ends of the axles, as shown in Figs. 1, 3, and 4, and being retained thereon by suitable pins. By this means draft is applied to the axles both inside and outside of the wheels; hence there is a more direct pull 60 upon the axle than when the draft is applied at one point only, the strain being thus more evenly distributed, risk of breakage lessened, and the wheels caused to quickly and accurately follow any change in the direction of the draft, 65 for as the outer end of the draft-bar is moved to right or left there is a definite swinging movement of the axle and a proper change in the position of the wheel, as will be readily understood on reference to Figs. 1 and 4. 70

To the front end of each beam D of the cultivator are bolted a pair of plates, f, the front ends of which are bent so as to embrace a block, g, openings in the bars f, being adapted for the reception of two circular hubs, i, on the block, 75 so that the beam is pivoted to said block. The latter is pivoted to the frame B by means of a vertical bolt, m, so that a universal joint between the frames B and beams D is formed. The swinging movement of the beams on the 80 hubs i of the blocks g is limited, however, by transverse bolts n, which are adapted to slots n' in the block, so that the arch A is prevented from tipping forward or backward beyond a certain extent. To facilitate the manufacture 85 of the block g it is made in halves, as shown in Figs. 4, 5, 6, 7, and 8.

To a lug, p, on the rear end of each draft-bar J is hung an arm, M, a lug, q, on said arm projecting beneath the hollow stem a of the 90 axle G, and having a projection, s, adapted to the central opening of said stem, so that while the arm M is free to swing with the draft-bar and axle it cannot swing upward. (See Fig. 9.)

To the rear end of each arm M is pivoted a 95 runner, N, these runners bearing upon the ground and supporting the frame when the cultivator is being drawn to and from the field, as shown in Fig. 1, the beams D in this case being elevated and supported by arms P, projecting rearwardly from the arch. Each runner consists of a lever the short arm of which

projects above the arm M, and when the runner is in use bears upon a dog, w, Fig. 10, this dog being hung within a slot in the arm M, and having shoulders bearing on the top of said arm, so that when the parts are in the positions shown in Figs. 3 and 4 the runner is locked to the arm, so far as upward movement of its outer end is concerned. When it is not desired to use the runner, however, the latter may be moved so as to release the dog and permit it to be thrown up, as shown in Fig. 11, and the arm can then be thrown upward and forward to the position shown in Fig. 12, the dog being allowed to drop, so as to afford a support for the runner. When the runner is thrown down again, the short arm of the same will strike and lift the dog, which will then fall into place beneath said arm, so as to automatically lock the runner in position.

20 We claim as our invention—

1. The combination of the frame B, having eyes b b, the axle G, having a stem, a, adapted to said eyes, and the cap d, bearing upon the upper eye, b, and bolted to the upper end of the stem a, as set forth.

2. The combination of the frame B, having eyes b b, the axle G, having a stem, a, adapted thereto, the draft-bar J, hung to the said stem a, and the rod K, connected to the draft-bar and to the outer end of the axle, as set forth.

3. The combination of the frame B, the axle G, having a stem, a, adapted to eyes on the frame, the draft-bar J, and the runner-carrying arm M, hung to the draft-bar, and having a projection, s, adapted to a central opening in the 35 stem a, as set forth.

4. The combination of the frames B, the blocks g, pivoted thereto, and the beams D, the end plates, f, of which are pivoted to hubs i on said blocks g, as set forth.

40 5. The combination of the frames B, the pivoted blocks g, having slots n', and the beams D, having end plates, f, pivoted to the blocks g, and having bolts n, adapted to the slots n', as set forth.

45 6. The combination of the frames B, the bolts m, the blocks g, made in halves, and the beams D, with plates f, confining said halves, as set forth.

7. The combination of the arms M, the pivoted runners N, and the locking-dogs w, as set forth.

In testimony whereof we have signed our names to this specification in the presence of two subscribing witnesses.

PHILLIP HIEN.
ASMUS H. GRIMM.
